COMBINATION COMB AND LIGHTER

Joseph Wiesner, Miami Beach, Fla.

Application July 18, 1958, Serial No. 51,846

Term of patent 14 years

(Cl. D48—27)

Figure 1 is a perspective view of a combination comb and lighter showing my new design with the comb in retracted position;

Figure 2 is an end elevational view thereof as seen from the left of Figure 1;

Figure 3 is a perspective view thereof as seen from the opposite side and bottom of Figure 2; and

Figure 4 is a side elevational view thereof with the comb in extended position, with the teeth only partially disclosed and it being understood that said teeth cover the entire broken line area shown.

I claim:

The ornamental design for a combination comb and lighter, as shown and described.
